(57) **CLAIM**

The ornamental design for a electrical fish tape with dimensional markings, as shown and described.

DESCRIPTION

FIG. 1 is a front elevational view of a electrical fish tape with dimensional markings showing my new design, the rear elevational view being a mirror image thereof;

FIG. 2 is a top plan view thereof;

FIG. 3 is a bottom plan view thereof; and,

FIG. 4 is an enlarged side view, taken from the left side of FIG. 1.
